(57) CLAIM

The ornamental design for an implement depth control and display, as shown and described.

DESCRIPTION

FIG. 1 is an elevated front perspective view of an implement depth control and display showing our new design.

FIG. 2 is a front view of the implement depth control and display design of FIG. 1.

FIG. 3 is a left side view of the implement depth control and display design of FIG. 2.

FIG. 4 is a top view of the implement depth control and display design of FIG. 2.

FIG. 5 is a right view of the implement depth control and display design of FIG. 2.

FIG. 6 is a rear view of the implement depth control and display design of FIG. 2, the broken line showing of the connector locations being for illustrative purposes only and forming no part of the claimed design; and,

FIG. 7 is a bottom view of the implement depth control and display design of FIG. 2.
